BILL DISPENSING POCKETBOOK

Harry D. Baird, Baltimore, Md., assignor of fifty
per cent to Joseph Schlossberg, Baltimore, Md.

Application May 31, 1946, Serial No. 673,496

2 Claims. (Cl. 150—38)

1

This invention pertains to pocket books and more particularly to those of the bill-fold variety.

An object of the present invention is to provide a new and improved pocket book that will permit the removal of bills one at a time without exposing the contents to the public.

An additional object of this invention is to provide a new and improved pocket book that will permit the placing of a plurality of valued bank notes in a plurality of compartments and allow the user to withdraw individual notes from each of said compartments without drawing the remaining notes in said compartment into view of the public.

Other objects will become apparent as the invention is more fully set forth.

For a better understanding of the invention, reference is had to the attached drawings and the following description wherein a particular form of the invention is outlined by way of example while the scope and spirit of the invention is more specifically pointed out in the claims.

In the drawings:

Figure 1 is a top plan view of a bill-fold pocket book, embodying this invention;

Figure 2 is a side elevation of Figure 1;

Fig. 3 is a side elevation of one side of the pocket book with the flap open to show a bank note projecting from the slot and positioned to be extracted therefrom, and

Figure 4 is a sectional view taken along line 4—4 of Figure 2.

Similar reference characters refer to similar parts throughout the drawings.

In the structure indicated in the drawings, a pocket book comprises a double backed container 10 of leather or similar material of a suitable character. This container has slide fastener connections 11 on its edges to enable it to be quickly and effectively closed together. The upper backing 12 of the container has an open slot 13 in its middle portion of rectangular form. Inside the container are leaves 14 and 15 for holding cards of identification and general use. The slot 13 is reinforced with a metal framework 17 on its edges to strengthen and stiffen it. It is wide enough to permit money bills 18 to be readily pulled through the opening without opening the container.

A cover 19 is attached to the container and folds down on top of it, and is held in closed position by a snap fastener element 29. This cover is provided with a transparent plastic sheet 20 to form a pocket therewith.

2

The inside portion of the upper backing 12 has a very flexible flap 21 that is fastened to the backing 12 by the framework 17 at the slot 13 and is much longer than the container, when extended outwardly. Ordinarily the flap 21 is folded approximately at its middle to encase the dollar or other money bills placed in the container. This serves as a suitable barrier between the bills and container leaf and enables the paper money to be withdrawn easily.

The lower backing 22 is a continuation of upper backing 12 and is provided with a similar slot 23 and a framework 24, which operates similarly to that connected with the upper backing, 15 already described. A cover 25 similar to 19 and a continuation thereof is attached to the backing 22 and covers the bills 28 extending therethrough, and is held in closed position by snap fastener element 30. A flap 26 is provided for 20 use in connection with this backing. The purpose of having the double slotted arrangement is to permit the user to segregate different denominations of bills from each other to prevent mistakes in paying out money therefrom.

The bills are folded transversely on the approximate center in the form of V's and they are inverted alternately as indicated in the drawings. This arrangement permits the end 35 of the first-half 36 of the outside bill 18 which is bent in the form of a V at approximately its center 37 to extend up through the slot 13 as shown in Figure 4, to enable the bill 18 to be extracted from the pocket book. During the time the first-half 36 of the bill 18 is withdrawn through the slot 13, the second-half 38 of the bill 18 pulls the end 39 of the second bill 40 up towards the slot 13 through the frictional contact between the second-half 38 of the bill 18 and the first-half 42 of the second bill. The bill 40 is bent at approximately its transverse center 41 and has pending its first-half 42 and its second-half 43, while its center 41 rests on the end 44 of bill 18. The third bill which would be bent like a V would be added by placing its first-half between the second-half 38 of the bill 18 and the second-half 43 of the bill 40. The fourth bill would be inverted like the bill 40, etc. This provides a semi-chain arrangement so the last-half of the preceding bill will lead the first-half of the subsequent bill up through the slot before the preceding bill is completely removed from the pocket book. The bills 28 shown in the other side of the pocket book would be bent and positioned in their respective positions in a manner 45 similar to that enumerated above. The covers 50 of the subsequent bill up through the slot before the preceding bill is completely removed from the pocket book. The bills 28 shown in the other side of the pocket book would be bent and positioned in their respective positions in a manner 55 similar to that enumerated above. The covers

are raised when the bills are to be used and manipulated as described.

The bills are protected within the container by the slide fastener connections fastening the upper and lower backings securely together, but may be removed one by one in the manner stated as required without difficulty.

The frameworks 17 and 24 serve as chutes through which the bills are pulled and they avoid catching or tearing of the same.

While but one general form of the invention is shown in the drawings and described in the specifications it is not desired to limit this application for patent to this particular form, as it is appreciated that other forms could be made that would use the same principles and come within the scope of the appended claims.

Having thus described the invention, what is claimed is:

1. A pocket book of the character described comprising an outer U-shaped cover, an inside U-shaped container nested within said outer cover, a central container for holding cards and dividing said inside container into two compartments, a flexible flap in each of said compartments adapted to contain folded bills, said inside container and flexible flaps having adjoining slots therein to allow the removal of the folded bills therethrough, a slide fastener connecting the opposite free ends of the inside container and coop- 30

erating snap fasteners for securing the adjacent ends of said cover and of said inside container.

2. A pocket book as set forth in claim 1, a metal framework for reinforcing said aforementioned slots and for securing said flexible flaps to said inside container.
